FOLDING TABLE

John Kovats, Fairfield, Conn.

Application August 21, 1936, Serial No. 97,123

19 Claims. (Cl. 311—82)

This invention relates to folding tables, and especially card or game tables of the type having folding legs to be maintained both in extended and folded position, and wherein as disclosed and claimed in my copending application Serial No. 74,237, filed April 14, 1936, and issued as Patent No. 2,077,701, April 20, 1937, spring-urged pairs of toggle links are provided for holding the legs in said positions, and operating connections, including links extending substantially diagonally of the table top, are provided for conjoint positioning of all the legs.

An object of the present invention is to provide improved operating connections for effecting positioning of all the legs of the table through the manual operation of any one of the legs, and for providing improved connections such that when the legs are locked in extended position all may be released to be folded by the release of any one. Another object is to provide a releasing means as last referred to of such type that not only can a manually operated release actuator be operated at any one of the four corners of the table selected at random, but such release can be effected with considerable ease and with a natural movement by moving said actuator toward rather than away from or parallel to the marginal portion of the table top. These improved release actuators are located near the margin of the table top, each to be grasped by hand together with the table frame, so that the actuator may be operated easily by simply urging it toward the frame by a squeezing movement similar to that employed when closing a pair of pliers, this movement being familiar to most people and being simple and effective. A feature of the improved releasing means of the present invention, as just described, is the provision of a leverage system whereby use is made of the lever principle in reducing the operating force required and increasing the extent of travel of the part to be moved so that only a small hand pressure is necessary, operating through a relatively large travel or stroke, to unlock the legs of the table when the latter are in extended position.

Still another object is to provide operating connections between the legs wherein a single substantially diagonally extended link can serve each leg, and in that connection to provide a central structure at the underside of the table top to assist in mounting such links while at the same time strengthening a thin table top and permitting economies of material and time in fabricating the table.

Other features and advantages will hereinafter appear.

In the accompanying drawings:

Figure 1 is a bottom plan view of a table made in accordance with this invention, with the legs 5 in folded position.

Fig. 2 is a fragmentary detail bottom plan of one corner of the table, with the shown leg folded in under the bottom of the table top.

Fig. 3 is a fragmentary view of one corner of the table in vertical section on line 3—3 of Fig. 2, with the table upside down, and showing the leg of Fig. 2 folded down or collapsed.

Fig. 4 is a view similar to Fig. 3, but showing the leg extended, this view being taken on line 4—4 of Fig. 5.

Fig. 5 is a view similar to Fig. 2, but showing the leg of the last-mentioned view extended, and in section.

Fig. 6 is a fragmentary detail view, being substantially a vertical section, taken on the line 6—6 of Fig. 1.

As an exemplifying embodiment of the present invention is shown in the accompanying drawings, the invention is applied to a card table of the rectangular-top type wherein four legs 10 respectively fold or collapse to lie within and substantially to parallel one of the four straight wall elements of a marginal frame 11 on the underside of a table top 12.

Each leg 10 is secured to a plate 13 having a barrel 14 receiving a pin 15 carried by a bracket 16. Each bracket 16 is shown as fastened by screws in the corner formed by a pair of meeting sides of the frame 11.

The legs 10 are moved from the folded position shown in Figs. 2 and 3 to extended position as shown in Figs. 4 and 5 by an actuating mechanism including for each leg a pair of toggle links 17 and 18 hinged together at 19. The links are connected respectively to the legs and the table by pins 20 and 21, and are positioned so as to lock the legs when in extended position, and each link 18 has an arcuate slot 22 in which rides a pin 23 carried by the bracket 16, so that the movement of the link is limited thereby.

Each toggle link 18 is connected to a spring 24 having its other end shaped to form a loop which bears against an accommodately shaped concave cut-out in the bracket 16, this end of the spring being held by a pin 25 attached to the marginal frame 11. The spring 24 acts to urge the links 17 and 18 to either folded or extended straight positions, depending on whether the moving end of the spring lies above or below the pin 25.

21. Thus the spring may urge the leg into either extended or folded position from a dead center position intermediate these positions (refer to Figs. 3 and 4).

5. There is disclosed in my Patent No. 2,005,716 a means for operatively connecting all four legs, and the present invention is concerned in part with an improved form of said means.

As here shown, the means last referred to comprises four substantially radially extended single links 26 formed for lightness and strength of channel metal strips and flattened to spatulate form at opposite ends. The inner end of each of these links is pivotally connected, as indicated at 26a, 10 to the outer end of one of the four arms of a cruciform rocker plate 26', itself pivoted at 26'', at the center of the table top. The outer end of each of said links is pivotally connected, as indicated at 26b, to one of four like shaped plates, 15 constituting actuating levers 27, one for each of the legs 10.

Each of these actuating levers 27 is pivotally mounted by a pin 28 set in the appropriate bracket plate 16.

25. The rocker plate 26' is mounted atop a pad-structure 29 at the center of the table top of comparatively small yet adequate area. As shown, said pad-structure comprises a wood block 29' and an overlying metal wear plate 29''. The 30 top of pad-structure 29 is here shown at such distance below the underside of the table top 12, relative to the preferably somewhat higher locations of the levers 27 that the links 26, of channel form as aforesaid, and desirably of light- 35 weight sheet metal, are slightly sprung or tensioned in toward the table top as they approach their connections with the levers 27. Such a treatment of these links is now favored, as apparently tending to rigidify the general operating 40 assembly and give an improved action. Also, the wood block 29' stiffens that part of the table top 12 which, when the table top is of extreme thinness and light material, might otherwise betray after some use a tendency toward buckling 45 or other distortion. Furthermore, as shown in Figs. 1 and 6, said wood block, which can be glued to the table top, provides an entering material for ordinary wood-screws, so that such screws, as indicated at 29a, can mount the wear 50 plate 29''. The heads of these screws are cleared by the rocker plate 26' by virtue of the latter being upwardly centrally dished as shown in Fig. 6; and such dishing in turn serving as a convenient housing for the riveted end of the pivot 55 26'' for said rocker plate.

Each of levers 27 has an apertured arm 30 and an extension 31 having an upturned arcuate flange 32 with the center of curvature of such arc in the axis of pin 28. According to the invention, the arm 30 is longer than the extension arm 31, and preferably the longer arm is approximately twice the length of the shorter arm. I have found that by so constructing the lever 27 operation of the legs of the table is made 65 much easier and more positive. The extension 31 is provided with a recess 33 which opens into a slot 34 dividing the flange in two parts, and a pin 35 carried by the toggle 18 engages said slot so as to form a gear-connection between the 70 toggle and the lever 27. In effect, the lever 27 acts as a two-tooth contrate wheel, and the toggle 18 and pin 35 as a one-tooth pinion, each engaging the other to coordinate the movements of the lever and link. It will be seen that with the 75 legs and links 17 and 18 folded, the lever 27

will be positioned as in Fig. 2, and with the leg and links extended the lever will be positioned as in Fig. 5.

The parts just described, then, provide a means whereby when any one leg is moved toward folded or extended position, all the other legs move simultaneously and correspondingly.

According to the present invention, and with the parts last described omitted, the operating mechanism locally coupled to and associated with any actuating lever 27 can be operated, so as to allow any leg 10 to be moved separately and individually from closed to open or extended condition, that is, to redispone the toggle links 17 and 18 of a leg from the set thereof wherein such leg is locked in extended condition (here the aligned-center setting of said links shown in full lines in Fig. 4), to a releasing condition (here that of said links as shown in broken lines in Fig. 4). When the toggle links of any leg are 20 in the position last referred to, said leg, it will be understood, can be manually collapsed; while with the toggle links arranged as in Figs. 3, as they are arranged when their leg is collapsed, such links can be manually extended without 25 any necessity for varying the setting of the toggle links, merely by pulling the free end of the leg away from the table top.

However, with all the legs connected for joint movement and positioning of all by any one, due to the inclusion of the links 26 and the cruci-form plate 26', all the legs will be simultaneously extended from collapsed position when any one of them is manually extended from that condition. Also, all the legs will be simultaneously collapsed from extended condition as any one of them is manually collapsed from extended position, provided the toggle links 17 and 18 associated with that leg are first redispersed as last described, that is, changed from the full line 40 condition of Fig. 4 to the broken line condition of that view.

In order to provide for this, the present invention incorporates an auxiliary means, which here may be called the toggle-breaking means; one of 45 such means for each pair of toggle links 17 and 18. Each toggle-breaking means as here shown includes an arm 36 constituting a handle readily accessible offset from one of the levers 27 and pivoted to the latter at 26b, that is, somewhat 50 loose on the same pivot by which said lever 27 and link 26 are joined. Each handle 36, here shown of metal and of channel shape, and spatulate at its pivoted end as indicated at 36a, has a side flange offset from its spatula as shown 55 most clearly in Figs. 4 and 5, where such flange is marked 37.

This flange is so carried by its handle 36 that while the handle can be swung relative to the lever 27 as shown in full lines in Fig. 5, once it 60 is swung back to extend beyond said lever as shown in Fig. 2 it cannot be swung further in the direction last mentioned, due to the flange 37 being brought against a straight edge constituting a stop on lever 27.

A fixed reactance element 38 is provided for each handle 36, the same being shown as in the form of a wood-screw with a half-round head.

When all the legs are collapsed as shown in Figs. 1, 2, and 3, all the four handles 36 are considerably spaced from the marginal frame 11 below the table top. Then, furthermore, the spring 24 associated with each pair of toggle links 17 and 18, is only resiliently maintaining these links collapsed, and hence the legs, now collapsed, are 75

only resiliently so maintained. Thus, as aforesaid, all the legs can be moved from collapsed or folded condition to extended condition, on manually pulling any one leg away from the table top.

5. However, when the legs are extended, the springs 24 are holding the toggle links 17 and 18 in aligned-center settings as shown in Fig. 4, and hence said toggles are locked to hold the legs locked in extended condition. Then each handle 10 36 is disposed as shown by full lines in Fig. 5, being forced to that position by the adjacent reactance element 38. In order to break the lock of any pair of toggle links 17 and 18, that is, to throw the pivot between two links out of line 15 with the two other link pivots, and so release the associated leg for full movement toward collapsed or folded condition, it is merely necessary manually to engage the free end of the associated handle 36 and the frame 11 of the table, 20 such end now well away from said frame, and force said handle in toward said frame and in a direction parallel to the table top by a natural squeezing movement, as employed in operating a pair of pliers. During this operation, the reactance element bears against the flange 37 of 25 the handle and acts as a fixed fulcrum whereby the handle is rocked thereon as a lever of the first class, thus throwing the lever 27 to the broken line position of Fig. 5 as the handle is 30 moved from the full line position there shown to the broken line position indicated at 36'. This sufficiently rocks said lever to cause a movement of the pin 35 great enough to break the lock of the associated pair of toggle links.

35. The length of the arm 30 of the lever 27, being greater than that of the arm 31, is of particular importance here since it provides for breaking of the toggle links with only a very little force on the handle 36, since an advantage of leverage is 40 obtained through the lever 27. Furthermore, it is preferable to locate the fulcrum 38 so that a similar advantage in leverage is obtained when operating the handle 36 to engage said fulcrum. Referring to Fig. 5, the portion of the handle 36 between the fulcrum and the pivoted end 36a is 45 much shorter in length than the handle portion on the other side of the fulcrum. Therefore, by this system of levers 36 and 27 only a proportionately small pressure is required on the handle to 50 operate the toggles for breaking the legs.

As, incidental to this release of said pair of toggle links, the associated leg 10 moves slightly away from extended position, the three other pair of toggle links are similarly released and the 55 three other legs are similarly moved, due to the links 26 and the rocked plate 26'. Then any one of the legs can be manually forced to fully collapsed or folded position and with it the other three legs.

60. Variations and modifications may be made within the scope of this invention, and portions of the improvements may be used without others.

I claim:

1. In a folding table, the combination of a 65 rectangular table top; four legs; means for hinging the legs on the table top at the corners thereof for movement to and from extended and folded position; four pairs of toggle links, each connecting a different leg with the table top adjacent 70 to a corner of the latter; four levers one pivoted to the table top adjacent to each corner thereof, each of said levers having a short arm and a long arm; means partially carried by the short arm of each of the levers and partially carried by one 75 of the links of the neighboring pair of toggle

links for moving said pair to extend or collapse the connected leg; means operatively connecting the long arms of said levers thereby to interconnect the legs for simultaneous movement of all by one, said means including a rocker plate 5 pivotally mounted at substantially the center of the underside of the table top, and four links extending substantially diagonally of the table top, one end of each link being pivotally connected to said rocked plate and each link at its opposite end being pivotally connected to a different one of the levers at the long arm thereof; and separate locking means for each leg to maintain that leg in extended position, each such means including a spring acting on the pair of toggle 10 links associated with a particular leg.

2. In a folding table, the combination of rectangular table top; four legs; means for hinging the legs on the table top at the corners thereof for movement to and from extended and folded 20 position; four pairs of toggle links, each connecting a different leg with the table top adjacent to a corner of the latter; four levers, one pivoted to the table top adjacent to each corner thereof; means partially carried by one arm of each of 25 the levers and partially carried by one of the links of the neighboring pair of toggle links for moving said pair to extend or collapse the connected leg; means operatively connecting the other arms of said levers thereby to interconnect 30 the legs for simultaneous movement of all by one, said means including a rocker plate pivotally mounted at substantially the center of the underside of the table top, and four links extending substantially diagonally of the table top, one end 35 of each link being pivotally connected to said rocker plate and each link at its opposite end being pivotally connected to a different one of the levers at the arm thereof last mentioned; separate locking means for each leg to maintain that 40 leg in extended position, each such means including a spring acting on the pair of toggle links associated with the particular leg; and four rockable arms presenting handles, each arm being operatively connected to a different one of the 45 diagonally extended links whereby rocking of any arm when all the legs are extended partially readjusts all said pair of toggles links to release said locking means.

3. In a folding table, the combination of a 50 rectangular table top; four legs; means for hinging the legs on the table top at the corners thereof for movement to and from extended and folded position; four pairs of toggle links, each connecting a different leg with the table top adjacent 55 to a corner of the latter; four levers, one pivoted to the table top adjacent to each corner thereof; means partially carried by one arm of each of the levers and partially carried by one of the links of the neighboring pair of toggle links for moving said pair to extend or collapse the connected leg; means operatively connecting the other arms of said levers thereby to interconnect the legs for simultaneous movement of all by one, said means including a rocker plate 60 pivotally mounted at substantially the center of the underside of the table top, and four links extending substantially diagonally of the table top, one end of each link being pivotally connected to said rocked plate and each link at its 65 opposite end being pivotally connected to a different one of the levers at the arm thereof last mentioned; separate locking means for each leg to maintain that leg in extended position, each such means including a spring acting on the 70 75 links associated with a particular leg.

pair of toggle links associated with the particular leg; and a manually operable actuator comprising a handle pivotally carried by one of said levers and operable when the legs are extended 5 to assist in releasing said locking means by partially readjusting the toggle links.

4. In a folding table, the combination of a rectangular table top; four legs; means for hinging the legs on the table top at the corners thereof 10 of for movement to and from extended and folded position; four pairs of toggle links, each connecting a different leg with the table top adjacent to a corner of the latter; four levers, one pivoted to the table top adjacent to each corner 15 thereof; means partially carried by one arm of each of the levers and partially carried by one of the links of the neighboring pair of toggle links for moving said pair to extend or collapse the connected leg; means operatively connecting the other arms of said levers thereby to interconnect the legs for simultaneous movement of all by one, said means including a rocker plate pivotally mounted at substantially the center of the underside of the table top, and four links 20 extending substantially diagonally of the table top, one end of each link being pivotally connected to said rocker plate and each link at its opposite end being pivotally connected to a different one of the levers at the arm thereof last 25 mentioned; separate locking means for each leg to maintain that leg in extended position, each said means including a spring acting on the pair of toggle links associated with the particular leg; and a manually operable actuator comprising 30 a handle pivotally carried by one of said links and operable when the legs are extended to assist in releasing said locking means by partially readjusting the toggle links.

5. In a folding table, the combination of a rectangular table top; four legs; means for hinging the legs on the table top at the corners thereof 35 of for movement to and from extended and folded positions; four pairs of toggle links, each connecting a different leg with the table top adjacent to a corner of the latter; four levers, one pivoted to the table top adjacent to each corner thereof, each of said levers having a short arm and a long arm; means partially carried by the short arm of each of the levers and partially carried by one of the links of the neighboring 40 pair of toggle links for moving said pair to extend or collapse the connected leg; means operatively connecting the long arms of said levers thereby to interconnect the legs for simultaneous movement of all by one.

6. In a folding table, the combination of a rectangular table top; four legs; means for hinging the legs on the table top at the corners thereof 45 of for movement to and from extended and folded position; four pairs of toggle links, each connecting a different leg with the table top adjacent to a corner of the latter; four levers, one pivoted to the table top adjacent to each corner thereof, each of said levers having a short arm and a long arm; means partially carried by the short arm of each of the levers and partially carried by one of the links of the neighboring 50 pair of toggle links for moving said pair to extend or collapse the connected leg; and means operatively connecting the long arms of said levers thereby to interconnect the legs for simultaneous movement of all by one, said means including a rocker plate pivotally mounted at substantially the center of the underside of the table top, and four links 55 extending substantially diagonally of the table top, one end of each link being pivotally connected to said rocker plate and each link at its opposite end being pivotally connected to a different one of the levers at the arm thereof last 60 mentioned; separate locking means for each leg to maintain that leg in extended position, each said means including a spring acting on the pair of toggle links associated with the particular leg; and a manually operable actuator comprising a handle pivotally carried by one of said links and operable when the legs are extended to assist in releasing said locking means by partially readjusting the toggle links.

of the table top, one end of each link being pivotally connected to said rocker plate and each link at its opposite end being pivotally connected to a different one of the levers at the long arm thereof.

7. In a folding table, the combination of a rectangular table top; four legs; means for hinging the legs on the table top at the corners thereof for movement to and from extended and folded position; four pairs of toggle links, each connecting a different leg with the table top adjacent to a corner of the latter; four levers, one pivoted to the table top adjacent to each corner thereof, each of said levers having a short arm and a long arm; means partially carried by the short arm of each of the levers and partially carried by one of the links of the neighboring pair of toggle links for moving said pair to extend or collapse the connected leg; and means operatively connecting the long arms of said levers thereby to interconnect the legs for simultaneous movement of all by one, said means including two pairs of link members disposed diagonally of the table top, each pair interconnecting the long arms of diagonally opposite levers, and including means interconnecting the pairs of diagonally disposed link members with each other.

8. In a folding table, the combination of a rectangular table top; four legs; means for hinging the legs on the table top at the corners thereof for movement to and from extended and folded position; four pairs of toggle links, each connecting a different leg with the table top adjacent to a corner of the latter; four levers, one pivoted to the table top adjacent to each corner thereof, each of said levers having a short arm and a long arm; means partially carried by the short arm of each of the levers and partially carried by one of the links of the neighboring pair of toggle links for moving said pair to extend or collapse the connected leg; means operatively connecting the long arms of said levers thereby to interconnect the legs for simultaneous movement of all by one, said means including two pairs of link members disposed diagonally of the table top, each pair interconnecting the long arms of diagonally opposite levers, and including means interconnecting the pairs of diagonally disposed link members with each other.

9. In a folding table, the combination of a rectangular table top; four legs; means for hinging the legs on the table top at the corners thereof for movement to and from extended and folded position; four pairs of toggle links, each connecting a different leg with the table top adjacent to a corner of the latter; four levers, one pivoted to the table top adjacent to each corner thereof, each of said levers having a short arm and a long arm; means partially carried by the short arm of each of the levers and partially carried by one of the links of the neighboring pair of toggle links for moving said pair to extend or collapse the connected leg; means operatively connecting the long arms of said levers thereby to interconnect the legs for simultaneous movement of all by one, and a manually operable member pivotally carried by one of said levers on the long arm thereof, for actuating the lever and the other levers to break the toggles so that the legs may be folded.

10. In a folding table, the combination of a rectangular table top; four legs; means for hing-

ing the legs on the table top at the corners thereof for movement to and from extended and folded position; four pairs of toggle links, each connecting a different leg with the table top adjacent to a corner of the latter; four levers, one pivoted to the table top adjacent to each corner thereof, each of said levers having a short arm and a long arm; means partially carried by the short arm of each of the levers and partially carried by one of the links of the neighboring pair of toggle links for moving said pair to extend or collapse the connected leg; means operatively connecting the long arms of said levers thereby to interconnect the legs for simultaneous movement of all by one; a manually operable member pivotally carried by one of said levers on the long arm thereof, for actuating the lever and the other levers to break the toggles so that the legs may be folded; and a fulcrum for said manually operable member, carried by the table, whereby said member is operated as a lever in operating the leg-actuating levers, said fulcrum being placed so that the manually engageable portion of the operable member is longer than the pivotally connected portion of said member.

11. In a folding table, the combination of a rectangular table top; four legs; means for hinging the legs on the table top at the corners thereof for movement to and from extended and folded positions; toggle links connecting each leg with the table top; means acting on said toggle links for interconnecting the legs for simultaneous movement of all by one, said means including link members disposed diagonally of the table top, interconnecting diagonally opposite toggle links, and including means interconnecting the link members with each other; and a manually operable member pivotally carried by one of said diagonal links for actuating same and the other links to break the toggles so that the legs may be folded.

12. In a folding table, the combination of a rectangular table top; four legs; means for hinging the legs on the table top at the corners thereof for movement to and from extended and folded positions; toggle links connecting each leg with the table top; means acting on said toggle links for interconnecting the legs for simultaneous movement of all by one, said means including link members disposed diagonally of the table top, interconnecting diagonally opposite toggle links, and including means interconnecting the link members with each other; and a plurality of manually operable members, each pivotally carried by one of said diagonal links for actuating same and the other links to break the toggles so that the legs may be folded.

13. In a folding table, the combination of a rectangular table top; four legs; means for hinging the legs on the table top at the corners thereof for movement to and from extended and folded position; four pairs of toggle links, each connecting a different leg with the table top adjacent to a corner of the latter; four levers, one pivoted to the table top adjacent to each corner thereof; means partially carried by one arm of each of the levers and partially carried by one of the links of the neighboring pair of toggle links for moving said pair to extend or collapse the connected leg; means acting on the other arms of said levers for interconnecting the legs for simultaneous movement of all by one, said means including link members disposed diagonally of the table top and interconnecting diagonally opposite levers, and including means interconnecting the

link members with each other; and a manually operable member pivotally carried by one of said levers for actuating same and the other levers to break the toggles so that the legs may be folded.

14. In a folding table, the combination of a rectangular table top; four legs; means for hinging the legs on the table top at the corners thereof for movement to and from extended and folded position; four pairs of toggle links, each connecting a different leg with the table top adjacent to a corner of the latter; four levers, one pivoted to the table top adjacent to each corner thereof; means partially carried by one arm of each of the levers and partially carried by one of the links of the neighboring pair of toggle links for moving said pair to extend or collapse the connected leg; means acting on the other arms of said levers for interconnecting the legs for simultaneous movement of all by one, said means including link members disposed diagonally of the table top and pin-connected to diagonally opposite levers, and including means interconnecting the link members with each other; and a manually operable member pivotally carried by the pin connection between a lever and link for actuating same and the other levers and links to break the toggles so that the legs may be folded.

15. In a folding table, the combination of a rectangular table top; four legs; means for hinging the legs on the table top at the corners thereof for movement to and from extended and folded positions; toggle links connecting each leg with the table top; means acting on said toggle links for interconnecting the legs for simultaneous movement of all by one, said means including link members disposed diagonally of the table top, interconnecting diagonally opposite toggle links, and including means interconnecting the link members with each other; a manually operable member pivotally carried by one of said diagonal links for actuating same and the other links to break the toggles so that the legs may be folded; and a fulcrum about which the manually operable member pivots, carried by the table.

16. In a folding table, the combination of a rectangular table top; four legs; means for hinging the legs on the table top at the corners thereof for movement to and from extended and folded positions; toggle links connecting each leg with the table top; means acting on said toggle links for interconnecting the legs for simultaneous movement of all by one, said means including link members disposed diagonally of the table top, interconnecting diagonally opposite toggle links, and including means interconnecting the link members with each other; a manually operable member pivotally carried by one of said diagonal links for actuating same and the other links to break the toggles so that the legs may be folded; and a fulcrum about which the manually operable member pivots, carried by the table, said fulcrum being so placed that the manually engageable portion of the operable member on one side of the fulcrum is longer than the pivotally connected portion on the other side so that an advantage in leverage is obtained when operating the member.

17. In a folding table, the combination of a rectangular table top; four legs; means for hinging the legs on the table top at the corners thereof for movement to and from extended and folded position; four pairs of toggle links, each connecting a different leg with the table top adjacent to a corner of the latter; four levers, one pivoted to the table top adjacent to each corner thereof; means partially carried by one arm of each of the levers and partially carried by one of the links of the neighboring pair of toggle links for moving said pair to extend or collapse the connected leg; means acting on the other arms of said levers for interconnecting the legs for simultaneous movement of all by one, said means including link members disposed diagonally of the table top and interconnecting diagonally opposite levers, and including means interconnecting the

to a corner of the latter; four levers, one pivoted to the table top adjacent to each corner thereof; means partially carried by one of the links of the neighboring pair of toggle links for moving said pair to extend or collapse the connected leg; means acting on the other arms of said levers for interconnecting the legs for simultaneous movement of all by one, said means including link members disposed diagonally of the table top and interconnecting diagonally opposite levers, and including means interconnecting the link members with each other; a manually operable member pivotally carried by one of said levers for actuating same and the other levers to break the toggles so that the legs may be folded; and a fulcrum about which the manually operable member pivots, carried by the table.

18. The invention as defined in claim 15, in which the fulcrum comprises a screw which may be turned in or out to adjust the height of the fulcrum.

19. In a folding table, the combination of a rectangular table top; four legs; means for hingeing the legs on the table top at the corners thereof for movement to and from extended and folded positions; toggle links connecting each leg with the table top; means acting on said toggle links for interconnecting the legs for simultaneous movement of all by one, said means including link members disposed diagonally of the table top, interconnecting diagonally opposite toggle links, and including means interconnecting the link members with each other; a manually operable member pivotally carried by one of said diagonal links adjacent the table frame and at an angle thereto; and a fulcrum mounted on the frame to be engaged by the member for forming a lever thereof so that the diagonal links can be actuated to break the leg toggles from locked position by grasping both the operable member and the table frame, and urging these together. 20

JOHN KOVATS.
